ELECTRIC VENTILATING FAN

Jacobus C. van Rijn, Woodstock, N.Y.

Application July 31, 1959, Serial No. 57,022

Term of patent 14 years

(Cl. D26—7)

FIG. 1

FIG. 2

FIG. 3

FIG. 4

Fig. 1 is a side perspective view of an electric ventilating fan, showing my new design;

Fig. 2 is an opposite side perspective view;

Fig. 3 is an edge elevational view; and

Fig. 4 is a side elevational view thereof.

This application is a continuation-in-part of my co-pending companion application, Serial Number D. 51-149, filed June 2, 1958, which is now abandoned.

I claim:

The ornamental design for an electric ventilating fan, as shown and described.
